UNITED STATES PATENT OFFICE

ALFRED ORDE TATE, OF TORONTO, ONTARIO, CANADA

SCANNING DEVICE

Application filed May 22, 1929. Serial No. 365,031.

This invention relates to improvements in scanning devices and mountings for same, to be used in the art of television, as described in the present specification and illustrated in the accompanying drawings which form part of same.

The invention consists essentially of a novel mounting for a scanning band and particularly a scanning band similar to that described and claimed in my United States application, Serial No. 336,226, filed January 30, 1929.

In the above mentioned application I described and claimed an apertured band or belt lead over a driving drum and an idler drum. The apertures in a scanning device are preferably arranged in such a manner that only one aperture at one time will scan or register on the image to be scanned. In view of this, the size of the image which could be effectively scanned by means of the above mentioned apertured band is somewhat limited, as it requires a certain number of apertures to scan each vertical inch, providing the scanning action is in a substantially horizontal direction, and these apertures are preferably laterally spaced from each other a distance equal to or greater than the width of the area to be scanned. Supposing the surface to be scanned was four inches in width and it required twenty apertures to scan each vertical inch of area.

Thus to completely scan this image from bottom to top or top to bottom, a band of approximately one hundred and sixty inches in length would be required, having eighty apertures therethrough, each spaced from its neighbouring aperture by a distance of four inches, and in order to scan the image completely from bottom to top and top to bottom to effect an undulatory scanning movement so desired in television, it would require a band of twice this length, or approximately three hundred and twenty-five inches. It is quite evident that a band of this length would require considerable space to accommodate it if it were mounted over a single driving drum and an idler drum. In the following specification and drawings, I show another method of mounting the scan-

ning band whereby an endless band of indefinite length may be mounted and driven in a relatively small space, thus rendering it quite feasible for portable or stationary radio transmitting or receiving sets.

The chief objects of the invention, therefore, are to construct and arrange a mounting for a scanning band or belt whereby a relatively long scanning band may be mounted in a small space and whereby the entire band may be kept in motion at the same time; to appreciably increase the size of the scanning area or the image that may be scanned by an endless apertured scanning belt without materially increasing the space required for mounting said belt; to prevent undue strain at any point in a relatively long scanning belt; to maintain the tension on the belt practically uniform throughout its length; to provide a scanning device capable of scanning relatively large images for any desired period of time; to facilitate the synchronizing of a receiving scanning device with a transmitting scanning device by causing the scanning action of each set to be continuous regardless of the size of the image to be transmitted; and generally to provide a scanning device particularly adapted for use in the radio transmission and reception of relatively large images, simple in its constructional details and in operation and capable of accomplishing the aforesaid results and purposes.

In the drawings, Figure 1 is a plan view of the invention.

Figure 2 is a front elevational view of Figure 1.

Like numerals of reference indicate corresponding parts in the various figures.

Referring to the drawings, the numeral 10 indicates a suitable framework capable of supporting the various mechanisms involved in this invention. 11 is a cylinder or drum mounted on a spindle 12 journalled and supported in the frame 10 as at 13. 14 is a cylinder or drum similar to that shown at 11 and parallel therewith and mounted in the same plane as said cylinder 11 on a shaft 15 journalled in the frame 10 as at 16. Driving gears 17 and 18 rigid in respect to the drums 100

11 and 14 respectively, are mounted on the shafts 12 and 15, respectively. A drive shaft 19 suitably driven is journaled in the frame 10 as at 20 and has gears 21 co-acting with the gears 17 and 18. A plurality of pulleys or drums 25 are mounted on shafts 26 journaled in the frame 10 as at 27. An endless apertured scanning band 30 is mounted over the drums 11, 14 and 25. The drums 25 are so mounted on the frame 10 that the band 30 in passing over them will be led back and forth, as shown at 31. In this way, a band of considerable length may be led over the different drums or pulleys 25. The journal mountings for one or more of the drums 25 may be reciprocally carried on the frame 10 as at 28 and suitable springs 29 provided to impinge against the journals 28 to tension the band 30 and equalize the strain at all points, and also to prevent slackness of the band between any of the drums 25 or between the drums 11 and 14.

One or more of the drums 25 may be driven from the shaft 19, as illustrated at 25A, where a gear 35 rigid with the drum 25 meshes with and is driven by a gear 36 rigidly mounted on the shaft 19. It may be found advisable to drive either the drum 11 or the drum 14 from the shaft 19 or to depend only on the driven drums as at 25A to actuate the scanning band 30 mounted thereon. The drums 25 instead of being arranged as shown could be arranged in tiers and the band 30 led over them in a similar manner to that shown without changing the principles involved or going beyond the scope of this invention.

Suitable teeth 38 may be formed on the periphery of the driving drums and corresponding depressions or openings 39 adapted to be engaged by said teeth 38 may be formed in the band 30 to allow for a more positive drive of the band 30. The teeth 38 and the depressions or openings 39 are preferably so situated that they will not interfere in any way with the scanning action of the band 30. Suitable guide flanges 40 may be provided on any of the drums and positioned thereon to engage the edges of the band 30 and to retain said band in its proper path. The drums 11 and 14 are so mounted on the frame 10 that there will be a space between them as indicated at 42. The necessary electrical apparatus used in the art of television as indicated at 43, may be placed in this space at 42. As it is desirable to accomplish the undulatory scanning motion, or in other words to scan the image from top to bottom and bottom to top in a continuous action, scanning apertures 44 are formed in the belt 30 and are so arranged that each aperture will scan a section of the image adjacent the section scanned by the preceding aperture so that there will be no break in the continuity of the scanning action.

One or more of the drums 25 may be driven

from the shaft 19 as illustrated at 25A, where a gear 35 rigid with the drum 25 meshes with and is driven by a gear 36 rigidly mounted on the shaft 19. It may be found advisable to drive either the drum 11 or the drum 14 from the shaft 19 or to depend only on the driven drums as at 25A to actuate the scanning band 30 mounted thereon. The drums 25 instead of being arranged as shown could be arranged in tiers and the band 30 led over them in a similar manner to that shown without changing the principles involved or going beyond the scope of this invention. Suitable teeth 38 may be formed on the periphery of the driving drum and corresponding depressions or openings 39 adapted to be engaged by said teeth 38 may be formed in the band 30 to allow for a more positive drive of the band 30. The teeth 38 and the depressions or openings 39 are preferably so situated that they will not interfere in any way with the scanning action of the band 30.

Suitable guide flanges 40 may be provided on any of the drums and positioned thereon to engage the edges of the band 30 and to retain said band in its proper path. The drums 11 and 14 are so mounted on the frame 10 that there will be a space between them, as indicated at 42. The necessary electrical apparatus used in the art of television as indicated at 43, may be placed in this space 42. As it is desirable to accomplish the undulatory scanning motion, or in other words to scan the image from top to bottom and bottom to top in a continuous action, as 95 accomplished by my scanning belt described and claimed in my United States application Serial No. 336,226, filed January 30, 1929, scanning apertures 44 are formed in the belt 30 and are so arranged that each aperture will 100 scan a section of the image adjacent the section scanned by the preceding aperture so that there will be no break in the continuity of the scanning action.

It is to be noted, however, that I do not 110 wish to limit my invention to the use of any particular form or arrangement of the apertures in the scanning band, as practically any form of endless scanning band could be successfully operated by means of this invention.

This invention in operation is particularly adapted for the radio transmission and reception of relatively large images. The arrangement of the rotating drums 25 in different planes provides for the mounting thereon of an endless apertured scanning band or belt of indefinite length and requires minimum space. The tensioned reciprocally mounted journals for one or more of the drums 25 aids in retaining an even tension on the band 30 practically throughout its length and prevents sagging at any point and particularly between the drums 11 and 14. The teeth 38 on the driving drums engaging with the de- 120

pressions or openings 39 in the band 30 provides for a positive drive of the band 30, thereby eliminating any variation of speed and aiding the synchronism of receiving sets 5 with transmitting sets. The rotating drums 25 may be increased to an indefinite number and arranged either in rows or tiers, with the object of accommodating a belt of greater length to increase the possible area that may 10 be scanned without materially increasing the space required.

Through these means, a belt of indefinite length may be successfully operated.

What I claim is:

15 1. In a scanning device for use in the art of television, two drums rotatably mounted in the same plane on a frame and having a space between them, a plurality of auxiliary drums rotatably mounted in separate rows 20 and in the same plane, a flexible apertured endless belt led over said first-mentioned drums and back and forth over said second-mentioned drums, and additional means for positively rotating more than two of said 25 drums.

2. In a scanning device for use in the art of television, a frame, two parallel spaced drums rotatably mounted on said frame and in the same plane, a plurality of drums rotatably mounted on said frame, an endless flexible apertured band led over said first-mentioned drums and led over said second-mentioned drums, a mounting for certain of 30 said drums slidable in respect to said frame, and springs actuating said slidable mountings in the proper direction for tensioning 35 said band.

3. In a scanning device for use in the art of television, a frame, two parallel spaced 40 drums rotatably mounted on said frame and in the same plane, a plurality of parallel drums rotatably mounted on said frame, an endless flexible apertured band led over said first-mentioned drums and led over said second-mentioned drums, a shaft suitably journaled 45 in said frame and having gears rigidly mounted thereon meshing with and driving corresponding gears on certain of said drums respectively, projections on the periphery of 50 said driven drums engaging depressions or openings in said band, and resilient mountings for one or more of said second mentioned drums providing means for tensioning said band.

55 4. A scanning device for use in the art of television comprising a pair of drums suitably journaled and spaced, a plurality of pulleys journaled at varying distances from 60 said drums, an apertured belt trained around said drums and pulleys and reducing the reach of the belt on the pulley to within a distance approximately even with the stretch around said drums, and means for driving said belt.

65 5. A scanning device for use in the art of

television comprising an apertured belt mounted to form a front scanning stretch, means for bending the belt in reverse folds in the rear stretch and thereby contracting the length of the device, and means for positively driving the front scanning stretch and 70 said bending means.

Signed at the city of Toronto, this 5th day of April, 1929.
